CUSHION AND ELASTIC STUFFING

Isaac Singer, Hyman Singer, and Adolph Singer,
Montreal, Quebec, Canada

Application May 18, 1932, Serial No. 612,074

1 Claim. (Cl. 5—351)

The invention relates to cushions and elastic stuffing, as described in the present specification and illustrated in the accompanying drawing that forms part of the same.

5 The invention consists essentially in the application of elastic stuffings to resilient supporting pieces, as pointed out in the claim for novelty following a description in detail of some forms of the invention embodying the principles 10 of construction.

The objects of the invention are primarily to utilize a soft resilient material, such as sponge rubber for the construction of cushions, pillows, mattresses, linings and stuffings in upholstered 15 goods; to construct an article of this kind that will prove itself superior in durability and elasticity, as well as being adaptable for all furnishings suggesting comfort and health during rest- 20 ful hours, besides insuring sanitation and therefore freedom from the spread of disease; to aerate pillow mattresses and cushions and thereby maintain the sweetness of the surrounding atmosphere and contribute to the health giving and other properties hereinbefore mentioned 25 and materially minimize the dust nuisance; and generally to provide comfort, efficiency and stability in cushions and furnishings.

In the drawing, Figure 1 is a perspective view 30 of the cushion complete.

Figure 2 is a plan view of the interior frame and springs secured to one half of the case.

Figure 3 is a longitudinal sectional view of the cushion showing the interior.

Figure 4 is a cross sectional view of the cushion showing the interior.

Figure 5 is an elevational view showing one side of the cushion opened up.

Figure 6 is a plan view of an upholstered sheet 40 formed of the metallic springs and resilient frame.

Figure 7 is an elevational view of the upholstering sheet.

Figure 8 is a plan detail of a chesterfield cushion.

Figure 9 is a perspective view showing a modified form of stuffing.

Like numerals of reference indicate corresponding parts in the various figures.

50 Referring to the drawing, the cushion illustrated in Figure 1 is a pillow and is indicated by the numeral 15 and is preferably made of sponge rubber in one piece, cemented on three sides to form the closure and having rows of air-holes 17 along each side and across each end,

though these may be omitted or differently arranged if desirable.

The light coil springs 18 are arranged in longitudinal rows and these springs are held at their ends by the straps 19 which are also of 5 sponge rubber and extend from end to end of the pillow, both top and bottom in the inside of the case.

The individual straps 20 extend from the top and bottom longitudinal straps 19 and are folded over the end coils of the springs and both longitudinal and end straps are cemented to the case in the upper and lower sides, while the individual straps have their folds cemented together. 10

The limiting straps 21 are secured to limit the stretch of each spring and are in every instance fixed to chosen coils of the springs.

The spacing strips 22 are preferably made of sponge rubber and held at the ends by the lugs 20 23 of sponge rubber and these strips cushion the coils of the springs and eliminate noise as well as materially improving the elastic nature of the stuffing.

In Figures 6 and 7 a similar construction is 25 shown in an upholstering sheet. This is simply the pillow case opened up and stretched out with the resilient stuffing members secured to one side only, in much the same manner as 30 shown in the pillow arrangement.

In the use of these sanitary pillows, the air circulates freely inside as each pressure creates a pumping action which creates sufficient circulation of air to sanitize the pillow, thus insuring a wholesome and sweet pillow for bedding and other uses. 35

The longitudinal strips laid in the springs effectually stop rattle through contact of metal parts and at the same time afford a stability 40 in the construction that would otherwise be missing, though in some instances they may be replaced by rubber coated springs.

The bottom of these pillows or other cushion made according to this invention may be of 45 cotton or linen material, so that the envelope for the springs will receive plenty of air especially where a seat bottom is made of wire or cords.

One feature in the use of cotton is its lightness 50 and its percolating properties insofar as air is concerned, allowing a free circulation of air, which is a very excellent thing, when it is taken into consideration that this sponge rubber structure in use actually keeps the air thereabout in 55

movement and this is quite healthful and contributes to restfulness.

The cushion illustrated in Figures 8 and 9 is made of a sponge rubber envelope 43, having the 5 perforated sides 41, the bottom 44 being of sponge rubber or cotton if preferred and in that case the air holes will be unnecessary.

This cushion contains a mat of springs 45 usually wrapped in cotton and held together by 10 the connecting pieces 47 and clips, thus forming a unitary spring member which may be inserted in the envelope 43 and shape the said envelope.

The making of a spring mat is not novel in itself, but the use of a spring mat with and in a 15 sponge rubber envelope is novel and distinctly cooperates with the material for the mat in itself is of the shape desired in the cushion, and in the illustrations this shape is shown as rectangular, such as a cushion used for a chair in a ches- 20 terfield set, and it will be seen that the mat of springs may be removed at any time and the cushion cover thoroughly disinfected and cleaned, which in itself is quite an advantage.

The actual comfort of a cushion depends en- 25 tirely on the two materials, the springs made of metal of course, and the sponge rubber, itself a cushioning member, and the quick return to normal after the removal of the load is effected both in the material of the envelope itself and of course 30 in the springs.

The effect of the pressure is first and foremost the settling of the body in the material of the envelope, that is to say, in the resilient sponge rubber. This takes away all the sharper effect of the metallic springs, which often becomes quite 5 uncomfortable after a long sitting, and so far as is known sheet sponge rubber has not been combined with springs or used as an envelope for springs, therefore the association of these two materials in the particular manner described pro- 10 duces a new and useful article in the industrial art to which this invention belongs.

What we claim is:—

In a cushion, an envelope of sponge rubber having air holes therethrough, and an assembly 15 of light springs inserted in and shaping said envelope comprising a series of spaced springs, longitudinal sponge rubber spacing strips inserted centrally through each transverse row of springs intermediate of the height of each 20 spring in the row, means holding said spacing strips in position, limiting straps secured to the various springs, longitudinal strips of sponge rubber bound to the tops and bottoms of the springs and to the inner surface of the envelope 25 to cooperate with the envelope when the cushion is weighted.
